175,871

MOBILE HOUSE OR SIMILAR ARTICLE

Angus A. Webster, Saginaw, Mich., assignor to Howard Industries Inc., Saginaw, Mich., a corporation of Michigan

Application May 4, 1953, Serial No. 24,847

Term of patent 14 years

(Cl. D14—3)

Fig. 1

Fig. 2

Figure 1 is an enlarged perspective view of the full line portion of the drawing; and

Figure 2 is a side elevational view of a mobile house or similar article showing my new design.

The side opposite Figure 2 is substantially like the side shown.

I claim:

The ornamental design for a mobile house or similar article, as shown and described.
